UNITED STATES PATENT OFFICE.

CLARENCE L. THOMPSON, OF PORT WASHINGTON, NEW YORK.

CAR-SEAT.

1,253,196.

Specification of Letters Patent.

Patented Jan. 8, 1918.

Application filed July 18, 1916. Serial No. 103,911.

To all whom it may concern:

Be it known that I, CLARENCE L. THOMPSON, a citizen of the United States, residing at Port Washington, in the county of Nassau and State of New York, have invented certain new and useful Improvements in Car-Seats, of which the following is a specification.

My invention relates to car-seats of the type in which the back swings across the seat-cushion to reverse the seating direction thereof, and particularly to seats of the character disclosed in my Patent No. 1,196,902, granted September 5, 1916. The object 10 of this invention is to simplify and improve the construction of car-seats of this character, and particularly to provide means whereby, when the back is in either of its seating or operative positions, the back will 15 be positively locked against backward tilting movements, and the stresses caused by the pressure of the occupant of the seat against the back will be transmitted directly from the back standard to the rigid supports 20 of the seat. In my improved structure all pressure is removed from pivot pins or other connecting parts which are ordinarily subject to considerable shocks and strains in seats of the character referred to, 25 the mechanism being so arranged that stresses due to the weight of the back and also the stresses due to the turning effect on the back caused by the pressure of an occupant of the seat against the back are transmitted 30 to the rigid supports of the seat without passing through pivot pins or other bearing parts of small cross-sectional area.

The present application is, as to certain features thereof, a continuation of my application Serial No. 18,225, filed March 31, 40 1915, and as to certain other features it is an improvement thereon. It may also be considered as an improvement on the structure of my invention described and claimed in my Patent No. 1,196,902, referred to above, although it is to be understood that my present construction is not strictly limited in its applicability to seats of the character described in my said application.

50 In order that a clearer understanding of my invention may be had, attention is hereby directed to the accompanying drawings forming part of this application and illustrating certain embodiments thereof. In the drawings Figure 1 is a transverse vertical

sectional view of the car-seat, the back standard being broken away, Fig. 2 is a similar view showing the back in its midway position, Fig. 3 is a central vertical sectional view on the line 3—3 of Fig. 2, to an enlarged scale, Fig. 4 is a similar vertical section taken on line 4—4 of Fig. 1, Fig. 5 is a detail view of the outer side of the lower end of the back standard, Fig. 6 is a view similar to Fig. 2, illustrating a modification and Fig. 7 is an enlarged vertical section taken on line 7—7 of Fig. 6.

Referring to the drawings, the reference numeral 1 designates the pedestal which supports the car-seat at the aisle end thereof, the other end of the seat being supported either by a similar pedestal or from the side of the car body. The connecting rails 2 are mounted in the upper ends of the arms of the pedestal, the ends of said rails fitting in 60 sockets 3 carried by the end-plate 4 of the seat structure.

Rotatably mounted in the aisle end-plate 4 and in a similar plate at the wall end of the structure is an operating rod 5, the ends of 65 said rod fitting in sockets 6, secured to the inner sides of the end-plates. Mounted on the operating rod near the ends thereof are back-supporting bars 7, said bars having circular enlargements 8 at their upper ends, 75 said enlargements being formed with the outwardly extending circular flanges 9. The flange 9 on each bar 7 extends around the said circular enlargement and terminates 80 adjacent the side edges of the bars 7.

The back standard 10 is formed adjacent its lower end with a circular flange 11, which fits within the flange 9 of bar 7, the flange 11 extending partially around the enlarged circular end portion 12 of standard 10, 90 whereby, as the back is rocked in its swinging movement from one seating position to the other, the flange 11 will always be in contact with the flange 9 and will not extend across the stops between the lower ends of 95 the flange 9.

Means are provided for imparting the correct inclination to back standards 10 and the back carried thereby as the latter reaches its seating position at each longitudinal edge of the seat. As shown in the drawings, this means may, and preferably does, comprise a pair of parallel levers 13 at each end of the seat. These levers are pivoted to the end frame 4, as shown at 13', 100 105 110

13', the pivots 13' having their axes in a plane passing horizontally through the center of the operating rod 5 and equally distant therefrom, one on either side thereof. 5 The upper ends of these parallel levers are mounted on studs 14, 14, secured to the lower end of the back standard 10. This standard is pivotally secured to the back-supporting bar 7 by means of the engagement of 10 circular flanges 9 and 11 above referred to. Bar 7 and standard 10 are held in coacting position by any suitable means which shall not interfere with the rotative engagements of flanges 9 and 11. As shown, this means 15 may comprise a pin 15 extending through bars 7 and standard 10 at the center of the enlargement 8 of said bar. Pin 15 may be provided, if desired, with a portion 15' of 20 enlarged diameter between the bar and standard, and with heads or locking pins or the like at each end of the pin to hold the same in place. A small clearance should 25 preferably be provided about pin 15 in its passage through bar 7 and standard 10 to prevent the same taking the strain which would otherwise be transmitted through flanges 11 and 9.

The studs 14 on which the upper ends of parallel lever 13 are mounted are located on 30 opposite sides of pin 15, at equal distances from said pin, studs 14 being separated by a slightly greater distance than the pivots 13' at the lower ends of levers 13. The levers 13 are bent outwardly at their ends, their main 35 portions lying close together and slightly overlapping during the movements of the back. These parallel levers maintain the back standard 10 in proper position during its swinging movement from one side of the 40 seat to the other. The pivots 14 being a slightly greater distance from pin 15 than the pivots at the lower ends of the levers are from the pivot of the bar 7, the back standard will be given a slight rearward inclination 45 when it is thrown to either of its seating positions, as is shown in Fig. 1, it being understood that pin 15 is at the center of rotation of flanges 9 and 11, and would constitute an additional connection between 50 standard 10 and bar 7 if the circular flanges were not provided.

The back standard 10 is provided near its lower end and across the circular enlargement 12 with an outwardly extending flange 55 16 which is adapted to come to rest on the slightly inclined flange 17 of the adjacent end-plate, as is shown in Figs. 1, 3 and 4 of the drawings. The inclination given to the back standard in each of its operative positions by reason of the arrangement of levers 13 is sufficient to permit the flange 16 to seat 60 squarely on the flange 17 at each end of the end frame 4, the coaction of flanges 16 and 17 thus supporting the back standard at the 65 rearwardly and upwardly inclined angle,

which is desirable for the back. As is shown in the drawings, Figs. 1 to 4, the flange 16 extends entirely across the enlargement 12 of the back standard 10 at right angles to the longitudinal center line of the back 70 standard; also the supporting flange 17 is cut away at each end of the seat end 4, as is indicated at 17'. Accordingly a portion of flange 16 at one side of the center line of the standard will come to rest on the flange 75 17 when the back is in one of its seating positions, while a portion of the flange 16 on the opposite side of the center line will come to rest on the flange 17 at the opposite end of the seat end, when the back is in its 80 opposite seating position. The reason for this preferred arrangement will be explained hereafter.

Pressure applied in a rearward direction to the back-cushion, either because of the 85 pressure of the back of the occupant of the seat against the seat back, or because of the force exerted in reversing the seat back into one of its seating positions, imparts a turning effect to the back and the standards 90 about the axis 15 of the pivotal or rotative connection between the standard and its supporting bar 7. Such tilting or rotative effect would put an objectionable shearing stress on the pivots 14 of levers 13. This 95 effect would not be overcome by the seating of flange 16 on flange 17, either for the full length of flange 16 or for part of its length, as shown, because the standard would tend to pivot about the rear end of flange 16. Accordingly, I provide coacting flanges or stops suitably arranged on the end plate and standard to prevent such rotation of the back and to relieve the operating mechanism of the strains otherwise occasioned thereby. These 100 locking flanges comprise a pair of flanges 18 and 19 formed on the standard and a coacting flange 20 at each end of the end-plate 4. Flanges 18 and 19 incline upwardly, one toward the left and the other toward the right, 105 some distance below axial pin 15. These flanges may suitably be positioned at each side of the longitudinal center line of the standard with their lower ends joining. Flanges 20 incline upwardly, the one at the 110 left hand end of the end-plate toward the right and the one at the right hand end of the end-plate toward the left. Flanges 20 are so inclined and arranged that the flange 18 on the standard will come squarely into 115 contact with the flange 20 at the right hand end of the end-plate, and flange 19 will come squarely into contact with flange 20 at the left hand end of the end plate when the back reaches its seating position at each edge of 120 the seat. It will be noted that the movement of flanges 18 and 19 as the back approaches a seating position is the resultant of the movement of axis 15 about operating rod 5 as a center as bar 7 swings over, and 125 130

the slight rotation in the opposite direction of standard 10 about axis 15 due to the action of parallel levers 13.

Flanges 20 and the coacting flanges on the standard are inclined upwardly at an angle which is sufficiently sharp to prevent any rotation of standard 10 about axis 15 as a center, because of pressure applied to the back above axis 15. It is obvious that pressure applied to the back above axis 15 tending to tilt the back rearwardly presses the flange 18 or 19 firmly against flange 20 with a resultant positive locking of the back against such movement. It is obvious that the pressure of flange 18, for example, against flange 20, due to the tilting movement referred to, is exerted in the direction of the tangent to a circle drawn about the axis 15 as a center at each point of the flange 18. Accordingly, a positive lock is effected when the flange 20 is of an inclination considerably steeper than this tangent, flange 20 being located below the center of rotation 15.

If seating flange 16 on the back standard rests for its entire length on flange 17, there is a tendency for the back standard to pivot about the rear end of flange 16, when backwardly directed pressure is applied to the back above axis 15. If not prevented by the interposition of flanges 18 and 20 or 19 and 20, this would tend to cause a straightening out of the angle between standard 10 and arm 7, the rear end of flange 16 riding along flange 17. In the construction illustrated, this pivotal movement would apply objectionable pressure to pivots 14, 14 of levers 13 if flanges 18 and 20 or 19 and 20 did not prevent. Even with locking flanges 18, 19 and 20 there might be a slight pivotal movement about the rear end of flange 16 unless the angle of flange 20 and the coacting flange 18 or 19 were steeper than it otherwise would have to be. This difficulty may be overcome by cutting away the seating flange 17 for a distance at each end of the end-plate, as illustrated at 17', such that the flange 16 has a bearing on the flange 17 for a length which extends toward the adjacent end of the end-plate only to the longitudinal center line of the back standard, or to a point somewhat short of the longitudinal center line as illustrated. With this construction the rearmost bearing point of flange 16 is forward of the axes 15, so that when backward turning pressure is applied to the back, there is no point of contact between flanges 16 and 17 to the rear of the pivotal axis 15 which could act as a fulcrum to cause the objectionable turning movement of the standard described above.

With the arrangement illustrated, it will be seen that the back is locked against rearward rotation in each of its seating positions and that all strains and stresses are trans-

mitted to the fixed support. When the back is being reversed, its downward thrust is transmitted through flange 11 to flange 9 and supporting bar 7, flange 11 extending sufficiently below the axis 15 to have a firm support on the corresponding portion of flange 9. The flanges 9 and 11 are terminated at their lower edges, as described, in order to permit the upper ends of the levers 13 to extend between said flanges to the studs 14 and to properly operate between the enlargements 8 and 12 as the back is swung from one position to the other. When the back is at rest in one of its seating positions, the reaction of flange 18 or 19 against flange 20 and also of flange 16 against flange 17 presses flange 11 upwardly against the inner surface of flange 9, this stress also being transmitted by bar 7 to the operating rod 5 and end plate 4. The engagement of the circular flanges 9 and 11 provides a large and durable bearing surface about which the various stresses referred to may be distributed. It will be obvious that the levers 13 and their pivots will be entirely relieved of the strains occasioned by a passenger leaning heavily against the seat back.

A somewhat modified form of my invention is illustrated in Figs. 6 and 7. As here shown, the upper flange 17 of the end plate 95 may be entirely removed, thereby making it possible to extend the length of the seat-cushion the distance otherwise occupied by flange 17. In this case, the locking lugs 18 and 19 are provided on the standard as before, and seat against the lugs 20, 20 on the end frame in the same manner as already described to lock the standard against rotation. In place of the seating flange 17 of the first form of my invention, flanges 21, 21 may be formed on the end plate to be seated against by one side or the other of back-supporting bar 7, when the back is in one seating position or the other. It will be obvious that flanges 21, 21 may be so positioned as to perform the same function as flanges 17 in the first form of my invention, namely, to provide a seating surface of sufficient area and to form a suitable stop. In some cases, the coaction of flanges 18 and 19 with flanges 20 115 may be sufficient alone to not only prevent rotation of the back but also to sustain the same in its seating positions.

When the form illustrated in Figs. 6 and 7 is used, flanges 20 and 21 may be formed integral with a yoke or casting 22 in which the connecting rails 2, operating rod 5 and pivot pins 13' may all have their bearings. This simplifies the manufacturing operation and increases the ease and accuracy of assembling the device as the openings for the connecting rails, operating rod and pivot pins referred to may be drilled at exact centers in a multiple drill press or by a similar operation. In this case, the end plate 4 may 130

be welded to yoke 22, the end plate being a thin sheet of metal provided merely for the purpose of giving a finished appearance to the end of the seat.

5 It will, of course, be understood that the important feature of this invention is the locking of the back standard to a rigid part of the seat support in order to relieve the pivots and other parts of the back transporting mechanism of the backward tilting strains brought thereon when the seat is in use, this feature being combined as described, in the preferred form of my invention, with the circular interlocking bearing 10 flanges comprising the pivotal connection between the standard and back-supporting bar. While I have shown a seat movement in which parallel levers 13, 13 are used to govern the inclination of the back, it should be 15 understood that the invention is not restricted to this type of seat. It should also be understood that while the operating parts are shown for only one end of the seat, the said parts will be duplicated at the opposite end, unless equivalent mechanism is 20 there used.

What I claim is:

1. A car-seat comprising a support, back-supporting means pivoted thereto at its 30 lower end, a back standard pivoted to the upper end of said means, a supporting flange formed on the back standard, a flange formed on the support and adapted to be engaged by the flange on the standard when 35 the back is in one of its seating positions, a locking flange carried by the standard below the pivot connecting the same to said supporting means, and a rigid stop on the support adapted to be engaged by said locking flange when the back is swung into seating 40 position, said locking flange and stop being positioned to resist turning movement of the back caused by rearwardly directed pressure thereon above the pivotal connection of the back standard, substantially as set forth.

2. A car seat comprising a support, a back-supporting bar pivoted thereto at its lower end, a back standard pivoted to the 50 upper end of said bar, a pair of levers pivoted on opposite sides of the pivot of the supporting bar and connected at their upper ends to the standard on opposite sides of the pivot of said standard, a flange 55 formed on the standard, a flange formed on the support and adapted to be engaged by the flange on the back standard, an interlocking flange carried by the standard near its lower end, and a rigid stop on the support, said interlocking flange being adapted to engage said rigid stop on the support to lock the said standard against backward tilting strains, substantially as set forth.

3. A car seat comprising a support, a back 60 standard, means connecting said standard to

the support, maintaining it in proper position during its reversing movement, and causing it to assume a desired inclination as it approaches each of its seating positions, a supporting flange formed on the back 70 standard, a flange on the support adapted to be engaged by said flange on the standard when the back is in one of its seating positions, a locking flange on the back standard, a rigid stop on the support adapted to be engaged by the locking flange when the back is swung into seating position, said locking flange being at an angle to said supporting flange, and said locking flange and stop being positioned to resist turning movement of the back caused by rearwardly directed pressure thereon, substantially as set forth. 75 80

4. A car seat comprising a support, a back supporting bar pivoted thereto at its lower 85 end, a back standard pivoted to the upper end of said supporting bar, a flange formed on the back standard, a flange formed on the support and adapted to be engaged by the flange on the back standard, an interlocking 90 stop flange carried by the standard near its lower end, and a coöperating rigid stop on the support adapted to be engaged by the interlocking flange on the standard to hold the said standard against a backward tilting 95 movement.

5. A car seat comprising a back support, a back standard, a supporting flange on the back standard, a flange on the support adapted to be engaged by the flange on the 100 back standard, a locking flange on the back standard below the supporting flange, and a rigid stop on the support adapted to be engaged by the locking flange, said lock flange and its coöperating stop being abruptly inclined with respect to the supporting flange, whereby the said flange and stop will co-operate to lock the back standard against a backward tilting movement, substantially as set forth. 105

6. A car seat comprising a support, a back-supporting bar pivoted thereto at its lower end, and provided with a circular bearing flange at its upper end, a back standard having a circular bearing flange 115 adjacent its lower end, one of said flanges fitting within the other to form an interlocking bearing, a supporting flange formed on the back standard, a flange on the support adapted to be engaged by said flange 120 on the standard when the back is in one of its seating positions, a locking flange on the back standard below the axis of the circular bearing flange thereof, and a correspondingly shaped stop on the support 125 adapted to be engaged by said locking flange when the back is swung into seating position, said locking flange and stop being positioned to resist turning movement of the back caused by rearwardly directed pres- 130

sure thereon above the axis of said circular bearing flanges, substantially as set forth.

7. A car seat comprising a support, a back supporting bar pivoted thereto at its lower end, and provided with a circular bearing flange at its upper end, a back standard having a circular bearing flange adjacent its lower end, one of said flanges fitting within the other to form an interlocking bearing, a back carried by said standard, means for causing the back to assume a desired inclination as it approaches each of its seating positions on being reversed, a pair of flanges on the back standard below the axis of the circular bearing flange thereof, one inclined upwardly to the left and one inclined upwardly to the right, a pair of flanges on the support, one adjacent each end thereof, so positioned and shaped that one is engaged and firmly seated against by one of said inclined flanges on the standard when the back is in one seating position, and the other is engaged and seated against by the other of said inclined flanges when the back is in its other seating position, said flanges being positioned to resist turning movement of the back caused by rearwardly directed pressure thereon above the axis of said circular bearing flanges, substantially as set forth.

8. A car seat comprising a support, back-supporting means pivoted thereto at its lower end, a back standard pivotally connected to the upper end of said means, a pair of flanges on the back standard below the center of the said pivotal connection thereof, one inclined upwardly to the left and one to the right, a pair of flanges on the support, one adjacent each end thereof, so positioned and shaped that one is engaged and firmly seated against by one of said inclined flanges on the standard when the back is in one seating position, and the other is engaged and seated against by the other of said inclined flanges when the back is in its other seating position, said flanges being positioned to resist turning movement of the back caused by rearwardly directed pressure thereon above the axis of

said circular bearing flanges, substantially as set forth.

9. A car seat comprising an end plate having a seating flange adjacent each end thereof, a longitudinal rod secured to said plate, an arm pivoted at its lower end on said rod, a back standard pivotally connected to the upper end of said arm, a back carried thereby, a seating flange on said standard, extending on both sides of the axis of the pivotal connection between the standard and arm, said flange on the standard being adapted to bear, for a part only of its length, on one of said end plate flanges, when the back is in either seating position, said end plate flanges having the outer ends of their bearing surfaces at such points that the flange on the standard has no bearing on the outer side of the axis of said pivotal connection, substantially as set forth.

10. A car seat comprising an end plate having a seating flange adjacent each end thereof, a longitudinal rod secured to said plate, an arm pivoted at its lower end on said rod, a back standard pivotally connected to the upper end of said arm, a back carried thereby, means providing a seating surface on said standard for each seating position of the back, said surface being adapted to bear on one of said end plate flanges when the back is in either seating position, a locking flange on the standard and fixed stops on the end plate, adapted to engage when the back is in either seating position, and arranged to resist backward turning movement of the back, said seating surface on the standard and seating flanges on the end plate being so arranged that said seating surface bears on either of said seating flanges at the inner side only of the axis of the pivotal connection between the standard and said arm, substantially as set forth.

This specification signed and witnessed this 14th day of July, 1916.

CLARENCE L. THOMPSON.
